UNITED STATES PATENT OFFICE.

HENRY L. NEWMAN, OF MARBLEHEAD, OHIO.

TROUSERS-SUPPORTING DEVICE.

1,152,204.

Specification of Letters Patent. Patented Aug. 31, 1915.

Application filed April 7, 1915. Serial No. 19,648.

To all whom it may concern:

Be it known that I, HENRY L. NEWMAN, a citizen of the United States, residing at Marblehead, in the county of Ottawa and State of Ohio, have invented a certain new and useful Improvement in Trouser-Supporting Devices, of which the following is a full, clear, and exact description, reference being had to the accompanying drawings.

10 The object of this invention is to provide a means on trousers for elastically engaging the supporting belt at the back, to support the trousers at that point while allowing a yielding movement of the trousers 15 with relation to the belt.

Another object is to so arrange the device that it may be simple, easily manufactured and readily attached.

A more specific object is to arrange such 20 supporting device in the form of a loop through which the belt extends and which may be concealed by one of the usual belt straps in the rear.

Another object is to prevent the belt moving 25 upwardly with relation to the trousers, sufficiently to come over the top of the same adjacent the point of the yielding support.

The above and other features of my invention are hereinafter more fully described 30 in connection with the drawings, and the essential characteristics are set forth in the claims.

In the drawings, Figure 1 is a rear elevation of a portion of a pair of trousers showing 35 the supporting belt with my supporting device embracing the same; Fig. 2 is a vertical cross section through the belt and supporting device and showing the means for preventing the trousers folding beneath the 40 belt; Fig. 3 is an elevation of a plate sewed inside of the trousers opposite the yielding support.

Referring to the drawings by reference numerals, 10 indicates a pair of trousers 45 having the usual belt straps 12 and 13 at the sides, and provided with belt straps (not shown) in the front, through which the belt 14 extends. Between these side belt straps is the usual belt strap 25 in the middle of 50 the back of the trousers, which, as trousers are ordinarily made, is subjected to considerable strain when the wearer assumes a stooping or sitting position. This strain causes the trousers to draw on the body of 55 the wearer and is frequently the source of considerable discomfort. To prevent this,

I prefer to secure the belt to the trousers at the back, in a position normally below the upper edge (for example with the top of the belt an inch or so from the top of the trousers at this point), with a yielding means, allowing the movement of the belt with relation to the trousers, or, more specifically, allowing the trousers to move downwardly beneath the belt when there is a downward strain at the rear of the trousers.

15 indicates an elastic loop preferably made of ribbon-like elastic material, and sewed to the trousers at 16, at the lower end of the loop. This loop is adapted to receive the belt and allow a downward movement of the adjacent portion of the trousers with relation to the belt, at all times yieldingly supporting the trousers at this point. A thin 70 plate 18, which may be of thin metal or other stiff material, and shown as triangular in form, is provided with a slot 19, adjacent its lower edge, through which the threads 16 securing the loop 15, may extend, to secure 75 the lower edge of this plate in place adjacent the inside of the cloth of the trousers, opposite the loop. At the upper end of the plate is an eye 20, adapted to receive threads 21 for securing the same to the trousers, as 80 shown. This plate when in position, is covered by the usual depending skirt 22, secured to the upper edge of the inside of the trousers.

Now it will be seen that the trousers may 90 be drawn downwardly with relation to the belt at the point opposite the elastic loop, thereby giving substantially the entire rear portion of the trousers a yielding movement, preventing uncomfortable strains to 95 the wearer. It will also be seen that the stiff plate 18 prevents the trousers beneath the belt at the rear, folding under the belt and preventing the free return movement as the loop contracts after the strain is relieved.

100 It is desirable to cover the elastic loop with the usual rear belt strap 25, which is preferably sewed first at its lower edge to the trousers at 26, and then sewed to the upper edge of the trousers at 27. This loop 105 is shown in Fig. 1 as extending upwardly from the upper edge of the trousers, for clearness of illustration.

When the belt and trousers are in their normal position on the wearer, the elastic 110 loop draws the belt downwardly slightly, as shown in Fig. 1, which tends to cause a

tightening of the belt around the body of the wearer, and it is obvious that if he assumes a position which causes a longitudinal strain on the belt itself, the belt will be drawn straight around the wearer, the loop yielding upwardly and allowing a slight relative lengthening of the belt, thereby causing it to elastically embrace the body of the wearer, which is in itself a desirable feature. If the trousers to which my elastic supporting device is attached, are provided with buttons 28, at the rear, for suspenders, the positioning of the elastic loop should be such that the belt normally overlaps the lower edge 15 of the buttons so that it may slide upwardly over the same without the buttons interfering with this movement.

Having thus described my invention, what I claim is:

- 20 1. The combination, with a pair of trousers having belt straps, of a belt extending through such straps, and an elastic loop embracing the belt and secured to the trousers tending to draw the belt downwardly with relation to the trousers.
- 25 2. The combination, with a pair of trousers having belt straps, of an elastic loop embracing the belt at the rear of the trousers and secured to the trousers below the belt, and a stiff plate secured to the trousers inside of the loop and extending upwardly above the normal position of the loop.
- 30 3. The combination, with a pair of trousers having belt straps, of a belt extending therethrough, an elastic loop extending around the belt and secured to the trousers, a stiff plate having an opening at its lower

edge to receive threads for securing the same to the trousers adjacent the lower end of the loop and having an opening in its upper end for securing it to the trousers above the normal position of the upper end of said elastic loop.

4. The combination, with a pair of trousers, of a belt extending around the same adjacent the upper edge, a loop composed of a ribbon-like elastic material extending over the belt, a stiff plate inside the trousers adjacent the loop having an opening in its lower edge, threads extending through the loop, trousers and opening in the plate, means for securing the upper end of the plate to the trousers, and means for covering said loop while allowing the relative movement of the trousers and belt.

5. The combination, with a pair of trousers having belt straps, of an elastic loop at the back of the trousers adapted to extend over the belt and secured to the trousers below the belt, and means for stiffening the trousers adjacent the elastic loop.

6. The combination, with a pair of trousers having belt straps, of an elastic loop at the back of the trousers adapted to extend over the belt and secured to the trousers below the belt, and a strap for covering the elastic loop.

In testimony whereof, I hereunto affix my signature in the presence of two witnesses.

HENRY L. NEWMAN.
